UNITED STATES PATENT OFFICE.

ALBERT J. D. OHM, OF ASTORIA, NEW YORK, ASSIGNOR TO MAX SCHAFFER CO., A CORPORATION OF NEW YORK.

DESIGN FOR AN ARM FOR LAMP FIXTURES.

• **61,318.**

Specification for Design.

Patented Aug. 1, 1922.

Application filed November 29, 1921. Serial No. 518,693. Term of patent 3½ years.

To all whom it may concern:

Be it known that I, **ALBERT J. D. OHM**, a citizen of the United States of America, residing at Astoria, county of Queens, and State of New York, have invented a new, original, and ornamental Design for an Arm for Lamp Fixtures, of which the following is a specification, reference being had to the accompanying drawing forming part thereof.

Fig. 1 is a side elevation of the arm, and Fig. 2 is a bottom plan view thereof.

I claim:—

The ornamental design for an arm for lamp fixtures.

ALBERT J. D. OHM.
